(57) **CLAIM**

The ornamental design for a travel bag, as shown and described.

DESCRIPTION

FIG. 1 is a perspective view of a travel bag showing my new design;

FIG. 2 is a front elevational view of the travel bag.

FIG. 3 is a rear elevational view thereof.

FIG. 4 is a left side elevational view thereof.

FIG. 5 is a right side elevational view thereof.

FIG. 6 is a top plan view of the travel bag.

FIG. 7 is a bottom plan view thereof; and,

FIG. 8 is a perspective view of the travel bag in the open position.

The broken lines shown throughout the views are understood to represent stitching.
